UNITED STATES PATENT OFFICE.

JOHN F. MCKNIGHT, OF ST. LOUIS, MISSOURI, ASSIGNOR TO AMERICAN CAR AND FOUNDRY COMPANY, OF ST. LOUIS, MISSOURI, A CORPORATION OF NEW JERSEY.

CAR-ROOF.

1,170,550.

Specification of Letters Patent.

Patented Feb. 8, 1916.

Application filed July 8, 1915. Serial No. 37,920.

To all whom it may concern:

Be it known that I, JOHN F. MCKNIGHT, residing at 915 Olive street, St. Louis, Missouri, and being a citizen of the United States, have invented certain new and useful Improvements in Car-Roofs, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings: Figure 1 is a cross section of that portion of my improved car roof which extends from the side plate to the running board, the unshown portion corresponding to that portion illustrated. Fig. 2 is a plan view of the portion of the roof shown in Fig. 1. Fig. 3 is an enlarged section taken longitudinally of the roof on line 3—3 of Fig. 1. Fig. 4 is a side elevational view of a portion of the roof and the running board. Fig. 5 is an enlarged side elevation, illustrating the connection between the side plate of a car and a pair of roof sections at a joint of the latter. Fig. 6 is a section on line 6—6 of Fig. 5. Figs. 7, 8 and 9 are sections on the lines 7—7, 8—8 and 9—9, respectively, of Fig. 6, arrows denoting the directions of vision. Fig. 10 illustrates a modified form of roof. Fig. 11 is a longitudinal section therethrough, and is taken on line 11—11 of Fig. 10; and Fig. 12 is a plan view of portions of the roof shown in Fig. 10.

My present invention relates to metallic roofs, and particularly to what is known as all steel roofs, it being my purpose to produce a roof of this kind which shall be characterized by such rigidity, in a direction from one side plate to the other of the car carrying it, that spreading of the car sides is prevented, and so that the roof will support its own weight and that of trainmen having occasion to be upon it. Notwithstanding its rigidity, it is so designed as to have the quality of lightness. Another desirable property it possesses is its flexibility from end to end of the car, due to the in-

herent properties of the metal from which the roof sheets are formed and the relation of the parts within their lapping portions, by which it accommodates itself to the weaving motions of the car body when the car is in transit.

In my improved roof there are no perforations for bolts or rivets which will allow water to seep through and damage the contents of the car, or through which water may find its way to rust and disintegrate the means for securing roof sections together. And, in adapting the roof to protect itself from the results of inclement weather, and other moisture-producing conditions, provision is made for draining all of the joints between roof sections.

An advantageous feature is that part of the design of the roof sheets and the relation of the latter to the side plates of the car, which gives ventilating communication between the interior of the car and the exterior, making the transportation of perishable lading feasible.

Other advantages not specifically mentioned, but becoming manifest hereinafter, are all to be considered as coming within the scope of the present invention.

Referring in detail to the parts, 1 indicates the side plate of a railway car, it being understood that two such side plates are present in the car superstructure carrying the roof, each extending longitudinally along the upper side edges of the superstructure and on opposite sides of the car, as is common in car construction. Side plate 1 is shown as being a commercial Z-bar, but it may be a pressing or a rolled or pressed shape of other form. Roof plates 2, successively arranged longitudinally of the car and interlocking with each other, extend transversely of the car from one side plate 1 to the other (not shown) on the opposite side of the car. Each plate 2 constitutes a roof section and between the side plates is preferably, but not necessarily, arcuate, and is downturned at said side plates.

One edge of each roof section or plate that extends transversely of the roof is pressed to form a channel 4, and the opposite transversely disposed edge is pressed to form a channel 3, extending outwardly from and paralleling which is a flange 6. Channel

4 preferably approximates the cross sectional contour of channel 3, but is of slightly larger dimensions, so that channel 3 of one roof section may fit into channel 4 at the 5 adjacent edge of the adjoining roof section, flange 6, projecting from the embraced channel 3, lapping the top of the next roof section 2.

The pairs of fitted or interlocking channels 3 and 4 are illustrated as being co-extensive with those edges of the roof sections or plates which lie transversely of the roof, and they assume the functions of carlines. Associated channels 3 and 4 thus create 10 carlines formed by interlocking portions of adjoining roof sections, the carlines manifestly being integral parts of said roof sections or plates. Due to there being no riveting of the overlapping and interlocking portions of adjoining roof sections to each other, the channels 3 and 4 forming each carline, are flexible and self-adjustable to each other to whatever degree is required by the weaving motions of the car when it is 15 traveling. For the same reason there is flexibility in the roof from one end thereof to the other.

The plates constituting the roof sections 2 usually are heavier or thicker than those 20 commonly used for steel roofs, giving adequate strength to the carlines formed by channels 3 and 4 and to the main body portion between said channels, making said roof sections self-sustaining between the car side 25 plates 1. Though very strong, the comparatively few parts that form the roof, and, in the preferred form, the elimination of a roof frame separate from the roof plates, and ordinarily present in cars, gives a highly 30 desirable lightness to the roof.

Notwithstanding the lack of the riveting of associated channels 3 and 4 together and their flexibility, there is small likelihood of an appreciable amount of water resulting 35 from rain, melting snow or other sources, working its way underneath flanges 6 of roof plates 2. But, in case of a less perfect fit, for any reason, between lapping roof plates 2 than that indicated in the drawings, 40 or, when there is an abnormally heavy downpour of rain, for example, no water can seep through and damage the contents of the car, and there are no rivets uniting channels 3 and 4 about which erosive action 45 might be stimulated and disintegration set in.

Drainage of all joints between roof sections is provided for, so that any amount of water finding its way under flanges 6 of the 50 roof plates will be discharged over the sides of the car. As best seen in Figs. 6, 8 and 9, channels 4 are each furnished with a drainage corrugation 5 which extends across the roof to points a little above the side plates 55 1. Discernible in Fig. 6, corrugation 5

ceases at these points, the depending end portions of channel 4, each having a flat bottom which bears against the web of one of the side plates 1. In proximity to and beginning above the points of termination of 60 the ends of corrugations 5 in channels 4, corrugations 7 begin in the end portions of the outer and embraced channels 3, and each corrugation 7 extends downwardly to the lower flange of one of the side plates 1. 65

The lower ends of corrugations 7 are cut away, the beveling of their lower ends, as shown in Figs. 5 and 6, illustrating a good mode of so doing, to supply exits from the drain passages formed by corrugations 5 70 and 7, and which passages extend without obstruction through the carline-forming joints of roof sections 2 from side to side of the car. The flow of any water that may have penetrated the joint between any plate 2 and the flange 6 lapping it uninterruptedly traverses the drain passage and escapes through the exits at the bottom of corrugations 7. The flat bottom or the back of each depending end portion of each channel 4 bears against the outer face of one of the side plates 1, separating or spacing the main portion of the roof section or plate 2 from the web of said side plate, the roof sections 2 extending to the bottom flanges of 75 side plates 1 on opposite sides of the car, and being supported thereby. The roof is secured in place by bolts or rivets 8, which pass through the main part of the roof sections 2 and the web of the adjacent side 80 plate 1. Where these bolts 8 occur, the roof plate 2 and the web of the side plate 1 are spaced from each other by fillers 9, each having flanges 10, bearing against roof sections 2, and a lip 11, which bears on top of 85 side plate 1 and prevents rotation of the filler. The spacing of the roof sections 2 between associated channels 3 and 4 from 90 the webs of the side plates 1, forms ventilating chambers B opening to the car interior 95 over the top of the side plates, which chambers communicate with the exterior through notches 12 in the bottom of the roof sections 2. 100

As best shown in Figs. 1 and 3, a saddle 115 clip 13 is secured to flange 6 of the roof section or plate 2 by rivets 17, which are countersunk in flange 6, and do not extend into and connect the part of the adjacent roof section 2 underlying flange 6 to that flange. 120 A running board saddle 16 is bolted to an upstanding flange of saddle clip 13 and supports a running board.

Referring to Figs. 10, 11 and 12, a modified form of roof is illustrated, in which a 125 sub-framing, comprising carlines 14, attached to the side plates 1, and purlins 15, support the roof plates, thereby permitting the use of much lighter plates. As shown in Fig. 11, there are depressions 18 in the 130

purlins 15, which fit around the channel-shaped corrugations 3 and 4, and restrain the latter from longitudinal movement.

Instead of making use of saddle clips, like 5 clips 13 in the form of roof illustrated in Figs. 1 to 9, inclusive, the flange 6 of the roof plates 2 is upturned at 6° where it passes under the running board, at the center of the car in this modification of the 10 roof, and the running board-supporting saddle 16 is bolted to it. It is also to be noted that, as in the type of roof first described, no bolts or rivets secure adjoining roof plates 2 to each other, the interlocking channels 15 3 and 4 holding the sheets securely 20 together and forming a flexible but practically weather proof joint. The roof sheets are secured to the side plates 1 by bolts or rivets 8 only sufficiently to prevent their separating from the car. Also, throughout 25 their width each sheet is rigid enough to maintain its own shape and prevent the spreading of the car sides, while the joints between roof sections or plates 2 allow a transverse motion to accommodate the uneven strains due to the twisting or weaving motion of the car body. In other respects, 30 the roof conforms to the construction of that shown in Figs. 1 to 9, inclusive.

The roof herein disclosed is simple to manufacture and assemble, and is weather-proof, self-sustaining and inexpensive. It also adapts the car to which it is applied to transport perishable lading, and is applicable to many types of cars. The side plates 35 1 are illustrated as of Z-shape in cross section though it is to be understood that any form of side plate which is provided with a vertical web or flange positioned in the plane 40 of the web 1^a may be substituted, within the present invention, it being considered advisable to employ such vertical web or flange and connect the roof sheets thereto. Thus it will be evident that, in the preferred form, 45 the top flange of the Z-shaped side plate may be omitted while in the form shown in Figs. 10, 11 and 12 the top flange 1^b is essential, if it is desired to rest the carlines thereon as illustrated.

50 What I claim is:

1. In a car roof, a plurality of self-sustaining metallic roof plates comprising main body portions and lapping edge portions, said edge portions of adjoining plates 55 flexibly interlocking and being shaped to form roof sustaining members in combination with a side plate of Z-shape with which said plates are connected, but over which said roof plates extend without support from the upper portion thereof.

2. In a car roof, side plates each having a vertical portion and a roof plate support at its bottom portion, a plurality of self-sustaining metallic roof plates adapted to extend across a car and to said roof plate sup-

ports and being secured to said side plates, said roof plates clearing the tops of said side plates and each having a main body portion and a plurality of edge portions lapping others of said roof plates, said edge portions of adjoining roof plates interlocking and being shaped to form carline-like members extending to the roof plate supports of said side plates. 70

3. In combination in a car roof, successively arranged self-sustaining metallic roof plates, each plate having a relatively smooth body portion and lapping edge portions, the latter having channeled depressions, the channeled depressions of adjoining roof 80 plates fitting into each other without attachment and flanges within the lapping portions projecting from fitted channeled depression portions over said body portions of adjacent roof plates. 85

4. In combination in a car roof, successively arranged self-sustaining metallic roof plates having body portions and depressed channeled portions, the channeled portions of adjacent plates fitting into each 90 other without attachment to each other and flanges projecting from fitted channeled portions lapping said body portions of adjoining roof plates.

5. In combination in a car roof, metallic 95 roof plates adapted to span the sides of a car and having flexibly interconnected depressed channel portions lapping and conforming to the adjacent contour of adjoining roof plates, and means adapted for the 100 attachment thereto of a running board saddle extending from said lapping and conforming portions of said roof plates.

6. In combination in a car roof, metallic 105 roof plates having flexibly interconnected portions and other portions extending from some of the portions that interconnect, said extending portions lapping adjacent roof plates, running board saddle securing devices mounted on said roof plate extending 110 portions and means fastening said saddle securing devices to said roof plate extending portions.

7. In combination in a car roof, side 115 plates, lapping metallic roof plates extending over said side plates, there being channeled portions in said lapping portions of the roof plates, those of adjoining roof plates being interconnected and cooperating with depression-forming portions in said interconnected channel portions creating an open-ended duct for discharging water over said side plates. 120

8. In combination in a car roof, side 125 plates, lapping metallic roof plates extending over the side plates, there being channeled portions in adjacent edges of adjoining roof plates, a channeled portion of each lapping roof plate fitting into a channeled portion of the adjoining roof plate, a de- 130

pression-forming portion in the fitting channeled portion of one roof plate and extending between said side plates to points adjacent them, and depression-forming portions in the associated channeled portion of the other roof plate creating with the depression-forming portion of the first mentioned channel portion a continuous open ended passage for discharging water over 5 said side plates.

9. In combination in a car roof, side plates, successively arranged self-sustaining metallic roof plates extending over the side plates and being supported on flanges thereof, and flexible joints connecting said roof plates and bearing against the side plates, said roof plates being apertured near their places of support and forming with said side plates between said flexible joints ventilating 15 chambers communicating with the interior and exterior of the car.

10. In combination in a car roof, side plates, successively arranged self-sustaining metallic roof plates extending over 25 the side plates and being supported thereby, flexible joints connecting said roof plates and bearing against the side plates, non-rotative spacing devices separating said roof and side plates between said flexible 30 joints and means clamping the spacing devices and roof and side plates together, whereby ventilating chambers are formed between said roof plates and side plates.

11. In combination in a car roof, side 35 plates having bottom flanges, successively arranged metallic roof plates extending over

the side plates and supported thereby, depressed joints connecting said roof plates and bearing against said side plates, portions of the roof plates between said joints 40 being spaced from said side plates, said bottom side plate flanges closing the spaces between the lower portions of said roof plates and side plates and communicating passages between the exterior and said spaces and the 45 latter and the interior of a car.

12. In combination in a car roof, side plates having bottom flanges, connected roof plates extending over said side plates, spaced from portions of the latter and supported thereby, said bottom flanges closing the bottoms of the spaces between said roof plates and side plates and ventilation passages from the exterior to said spaces and from the latter to the interior of a car. 50

13. In combination in a car roof, Z-shaped side plates, successively connected roof plates extending over said side plates to form passage-ways over the same and having portions spaced from the web portions of the 60 side plates, the bottom flanges of said Z-shaped side plates closing the bottoms of the spaces between the roof and side plates, and ventilation passages through the roof plates within the zone of said spaces. 55

In witness whereof I have hereunto set my hand in the presence of two witnesses.

JOHN F. McKNIGHT.
